UNITED STATES PATENT OFFICE.

DARE SIPES, OF BETHEL SPRINGS, TENNESSEE.

KNIFE ATTACHMENT FOR REVOLVERS.

Application filed March 13, 1924. Serial No. 698,994.

To all whom it may concern:

Be it known that I, DARE SIPES, a citizen of the United States, residing at Bethel Springs, in the county of McNairy and 5 State of Tennessee, have invented certain new and useful Improvements in Knife Attachments for Revolvers, of which the following is a specification.

This invention relates to new and useful 10 improvements in knife attachments for revolvers, pistols and analogous firearms, and has for its principal object to provide a device which is of such a construction as to enable the use of either the revolver or 15 knife independently.

Another important object of the invention is to provide a knife attachment of the above mentioned character, wherein the same is adapted to be supported in such a position 20 upon the firearms as not to interfere with the use of the latter, means being further provided with the knife for preventing the accidental opening of the same.

A further object of the invention is to 25 provide a knife attachment for a revolver which is simple in construction, inexpensive, strong and durable, and further well adapted for the purposes for which it is designated.

Other objects and advantages of this 30 invention will become apparent during the course of the following description.

In the accompanying drawing forming a 35 part of this specification and in which like numerals designate like parts throughout the same,

Figure 1 is a side elevation of my invention showing the knife blade in a folded position,

Figure 2 is a fragmentary sectional view 40 of a portion of the revolver with the knife blade in an extended position, and

Figure 3 is a sectional view taken on line 3—3 of Figure 1.

In the drawing wherein for the purpose of 45 illustration is shown the preferred embodiment of my invention, the numeral 1 designates a revolver of any preferred form which is provided with the usual barrel 2 and stock 3. Depending from the barrel 2

50 of the revolver 1 is the extension 4. This extension is provided with the longitudinally extending slot 5 which extends for substantially the full length of the extension 55 and communicates with the bottom and forward end of the extension respectively in

the manner as clearly shown in Figure 2 of the drawing. This slotted extension may be conveniently referred to as an open ended sheath for reception of a knife blade to be 60 hereinafter referred to. It is to be observed that the sheath gradually decreases in depth from its free outer end to its inner end and the bottom thereof is curved downwardly adjacent its point of juncture with the body 65 of the revolver. This particular curvature of the bottom comes into play as will be set out later.

Adapted to cooperate with the longitudinally extending slot 5 provided in the extension 4, is the knife blade 6. The latter has its tang portion 7 pivotally supported within the slot 5 on the transversely extending pins 8 adjacent the forward end of the extension in the manner as clearly shown in 70 the drawing. Arranged in the upper portion of the longitudinally extending slot 5 is the spring 9 and the same is supported therein at its inner end by means of a transversely extending pin 10. The spring which 75 I use is simply a flexible metal strip, which is flat from end to end. When the inner end of the spring strip is inserted between the cross pin 10 and the curved bottom of the channeled sheath, a considerable portion of 80 the length of the strip lies in contact with the bottom of the sheath. This method of construction constitutes the means for placing the strip under tension. The outer end of the spring lever 9 is free and is adapted 85 to engage the upper edge 11 of the tang 7 when the blade 6 is in an extended position for the purposes well known in the art and in the manner as clearly shown in Figure 2 of the drawing. When the knife blade is 90 folded so that the cutting edge thereof extends into the slot 5 in the manner as shown in Figure 3 of the drawing, the outer end of the spring lever 9 will engage the lower edge 12 of the tang 7 whereby the blade will 95 be held in position within the slot in the extension against accidental displacement therefrom.

It will thus be seen from the foregoing 105 description, that a knife attachment for a revolver has been provided wherein the use of either the revolver or knife may be had without interference and furthermore the simplicity in which the knife attachment is associated with the revolver enables the same 110 to be easily and readily actuated whenever it is desired to use the same. When the knife

is in an extended position, it will be readily understood that the barrel 2 acts as a handle for the same. A device of this character may be manufactured at a very low cost and 5 obviates the necessity of having to carry a knife on one's person in addition to the revolver, thus combining two implements in one.

While I have shown the preferred embodiment of my invention, it is to be understood 10 that various changes in the size, shape and arrangement of parts may be resorted to without departing from the spirit of the invention and the scope of the appended 15 claim.

Having thus described my invention, what I claim is:

A revolver having its barrel formed on its under side with a channeled sheath, said 20 sheath being gradually decreased in depth

from its outer end to its inner end and the bottom thereof at the last named end being curved downwardly, a shouldered cutting blade having its tang pivoted between the outer ends of the side walls of the sheath, 25 said blade being adapted to be swung inwardly into the sheath when not in use, a cross pin extending through the side walls of the sheath and spaced a slight distance 30 downwardly from the intermediate portion of the curved bottom of the sheath, and a flat strip of spring metal having its inner end inserted between the pin and the bottom so as to flex the inner end portion of the strip through its contact with the bottom of the sheath, whereby to place its outer free end 35 under tension, said free end being adapted to bear on the tang of the blade.

In testimony whereof I affix my signature.

DARE SIPES.
